UNITED STATES PATENT OFFICE

CARL F. WOLTERS, OF MARIETTA, OHIO, ASSIGNOR TO REMINGTON RAND INC., OF BUFFALO, NEW YORK

SAFE HINGE

Application filed February 17, 1931. Serial No. 516,401.

This invention relates to improvements in safes and cabinets, and particularly to improvements in the hinge structure for mounting the doors.

5 An object of the invention is to improve the construction and appearance of safes and cabinets by providing a special hinge structure for mounting the doors forming a continuous hinge having parts cooperating to 10 mount the safe doors for free swinging movement and to retain the hinge parts in assembled relation.

Another object of the present invention is to improve this arrangement by providing 15 a hinge structure for a safe, cabinet, or any type of door structure which will be continuous and unbroken in appearance for the entire length of the door or swinging member. This is accomplished by connecting the usual 20 cylindrical hinge portions of the separated hinges with a spacing tube which is retained in position by the hinge pins themselves. This arrangement not only improves the appearance of the safe or cabinet but by a 25 special cooperative structure securely locks all of the hinge pins, except that of the topmost hinge, against unauthorized or accidental removal. By this arrangement, when the topmost hinge pin is locked against removal by any suitable means, all of the remaining hinge pins in the series are securely locked against removal.

It is a further object of the invention to provide a very simple construction for the 35 connections between the hinge pins and the connecting tubes, which will enable economical production thereof, and also permit ease in assembling with a safe or other like device.

40 Other features of this invention are more specifically set forth and shown in the following description and in the drawings.

In the drawings:

Fig. 1 is a perspective view of a cabinet 45 provided with the hinge connecting structure of the present invention.

Fig. 2 is a cross section through the center of one of the hinges shown in Fig. 1.

50 Fig. 3 is a partial front elevation of the cabinet with portions progressively broken

away to show the hinge and mounting structure.

Fig. 4 is a perspective view of the hinge pin, bearings, and connecting tube in partially disassembled relation.

Fig. 5 is a vertical section through a portion of the hinge showing the bearing arrangement.

In the drawings, the numeral 1 indicates the stationary portion or body of a cabinet. The body 1 is shown as being of the usual insulated type having a core 2 of insulation material and a finishing shell 3 of sheet metal which covers the core 2 and extends around the front edge of the core to form a door jamb 4. A reinforcing angle 5 is provided immediately within the steel shell at the front corners of the cabinet, and is formed with a series of spaced narrow slots 6. A series of similar slots are provided in the shell 3 in registry with the slots 6 in the reinforcing angle. The spaced recesses thus formed provide a mounting for the hinge sections 7, each hinge section having a plate portion 8 inserted within a recess and welded or otherwise secured to a side of the angle member 5. A number of tubular hinge knuckles 9 extend from the margin of the plate portion and are in aligned relation.

The doors 10 are also of the typical insulated construction, each having an insulated portion 11 enclosed by a shell 12. A hinge bar 13 is mounted on the front of the door immediately beneath the shell 12 and extends through the shell and beyond the outer edge 14 of each door to form a hinge mounting portion 15. This portion is rectangular in shape and extends for the entire height of the door. A plurality of hinge sections 16 are secured by their rectangular connecting portions 17 to the inner face of the extension 15 of the mounting plate. These members are spaced from each other and are each provided with a plurality of spaced tubular hinge knuckles 17 which upon assembly of the door with the cabinet are adapted to mesh with the knuckles 9 thereof.

In assembly, the doors are fitted to their respective sides of the cabinet by interfitting the hinge bearings of the cabinet with the

hinge knuckles of the door. As shown in Fig. 3, the knuckles of the cabinet hinge plates receive the knuckles of the door hinge plate. Anti-friction devices, such as the **6** thrust bearings 19, may be interposed between the pivot bearings of the cabinet hinge plate and the pivot bearings of the door hinge plate.

Each hinge assembly, as above described, is **10** secured by a suitable connecting member such as a hinge pin 20 having a cylindrical shank portion 21 inserted through the knuckles and ball bearings thereof. The pin 20 is provided with an enlarged head portion 22 notched at **15** its upper extremity to form a portion 21 of reduced diameter. The hinge pins are assembled with the hinges in progressive fashion, that is, the lower hinge pin is inserted first, then a cylindrical tube 23 of an inside diameter substantially equal to the reduced portion 21 of the hinge pin is mounted on the reduced portion 21 of the lowermost pin head. The other extremity of the tube is fitted with a spacing washer 24, which lies on top of such **25** tube end and is provided with a reduced portion 25, pressed within the tube. It will be obvious that the washer 24 may be substituted for in a number of manners including utilizing portions of the tube itself to form the orifice 26. On this basis the tube and washer is **30** considered as a spacing unit. The spacing washer is provided with an orifice 26 adapted to receive the protruding portion 21' of a hinge pin. The tube, together with its accompanying washer 24, is placed on reduced portion **35** 21 of the lower hinge pin and is in an angular position relative to the side of the cabinet, upon which it is swung into place with the washer abutting the bottom of the next succeeding hinge. The angular position **40** is shown at "A" in Fig. 3. Sufficient clearance is provided between the washer and the hinge to allow for this swinging movement and assembly. The top end of the tube 23 is then **45** locked against removal by the protruding portion 21' of the hinge pin of the next succeeding hinge which extends through the underlying spacing washer 24. In this manner, the tube assembly is secured against removal from the hinges by the hinge pins of two adjacent hinges, and the tube assembly secures, in turn, the lower of the hinge pins against removal against the direction of its insertion. The upper hinge pin in such **50** assembly cooperates with the tube by locking the top end against removal to prevent swinging movement thereof in the manner of its assembly. This method of assembly is progressively continued to the topmost hinge **55** during which each succeeding hinge pin locks the tube assembly of the underlying unit. The topmost hinge pin thus indirectly controls access to the locking means of all the underlying hinge pins. It will be apparent **60** that if the top pin is locked against removal, **65**

all of the hinge pins on that side of the safe will be likewise locked. With this purpose in mind, any type of lock or removable abutment device may be utilized to prevent removal of the top hinge pin. It is preferred to utilize the cover or top portion 28 of the cabinet for this purpose. This cover portion in usual construction is secured to the top of the cabinet from within and is provided with a ledge 29 extending beyond the body of the cabinet. **70** The ledge 29 immediately overlies and abuts the top of the uppermost hinge pin and when secured, retains the same against removal. **75**

In the above description it is not intended to limit the features of the invention to the specific structure set forth as it will be obvious that the principle of continuous hinge structure shown may not only be varied in structural detail but may be utilized with types of hinges other than for cabinet use. **80**

What is claimed is:

1. In a hinge construction, a stationary member and a swinging member, a series of spaced hinges connecting said members, a hinge pin in each hinge, said hinge pins each having a shank portion extending through its hinge and a head portion abutting one side of its hinge, tube means extending between adjacent hinges and having one extremity removably engaged on the head of a hinge pin of one hinge and its other extremity abutting an adjacent hinge, and means for retaining said last-named extremity in engagement with said adjacent hinge. **90**

2. In a hinge construction, a stationary member and a swinging member, a series of spaced hinges connecting said members, a hinge pin in each hinge, said hinge pins each having a shank portion extending through its hinge and a head portion abutting one side of its hinge, tube means extending between adjacent hinges and having one extremity removably engaged on the head of a hinge pin of one hinge and its other extremity abutting an adjacent hinge, and means on **100** said last-named extremity of said tube means for receiving a protruding portion of the shank of the hinge pin of the adjacent hinge whereby said tube means is locked against removal at both extremities. **105**

3. In a hinge construction, a stationary member and a swinging member, a series of spaced hinges including a top hinge, an intermediate hinge and a bottom hinge connecting said members, a hinge pin in each hinge, each hinge pin having a shank portion extending through its hinge and a head portion abutting one side of its hinge, a tube having one extremity mounted on the head of the hinge pin of the bottom hinge and the other extremity abutting portions of the intermediate hinge and retained against removal by a protruding portion of the hinge pin thereof, similar tube means having one extremity mounted on the head of the hinge pin of the **110** **115** **120** **125** **130**

intermediate hinge and the other extremity abutting portions of the top hinge and retained against removal by a protruding portion of the hinge pin thereof, and means on said stationary member abutting the head of the hinge pin of said top hinge to prevent removal thereof.

4. In a hinge construction, a stationary member and a swinging member, a plurality of spaced hinges each connecting the stationary member to the swinging member, a hinge pin in each hinge, each hinge pin having a shank portion extending through its hinge and a head portion abutting one side of its hinge and having a reduced portion, a tube extending between adjacent hinges and having one extremity engaging over the reduced portion of one hinge pin, a washer secured to the opposite extremity of said tube and having a face portion abutting the next adjacent hinge and a recessed portion for receiving a protruding shank portion of the hinge pin thereof.

5. In a cabinet construction having a door, a plurality of hinge members on said door and cabinet at spaced intervals having interconnected portions mounting said door on said cabinet for hinging movement, said interconnected portions projecting laterally outward from said door and cabinet in axial alignment, means extending between said laterally extending interconnected portions and cooperating therewith to provide a continuous lateral extension from said cabinet substantially coextensive with said door, and cooperating means on said hinge members and said means detachably retaining said means in position.

6. In a hinge construction a stationary member and a swinging member, a series of spaced hinges connecting said members, a hinge pin in each hinge, tube means extending between each pair of adjacent hinges in said series of hinges and engaged by portions of the hinge pins thereof, said pins and said tube means being mountable in progressive order relative a hinge at one extremity of said series of hinges, whereby said pins and tube means cooperate for locking interengagement.

7. In a hinge construction a stationary member and a swinging member, an upper hinge and a lower hinge connecting said members, a hinge pin removably mounted in each hinge, removable tube means extending between the hinges and engaging the hinge pin of the lower hinge against removal, and interengaging parts on the upper hinge pin and said tube means for retaining said tube means in position.

CARL F. WOLTERS.
